Company, East Pittsburgh, Pa., a corporation
of Pennsylvania

Application July 24, 1939, Serial No. 286,218

6 Claims. (Cl. 62—8)

This invention relates to mechanical refrigerating apparatus and more especially to a means for cooling and for reducing the vaporization of liquid refrigerant in a capillary flow impedance device.

Capillary tubes forming a passage of relatively small diameter and great length are used in mechanical refrigerating apparatus to maintain a pressure differential between the condenser and the evaporator. Such tubes are subject to a refrigeration loss due to the fact that the pressure in the tube at the evaporator end thereof is nearly at the pressure of the evaporator and that some of the refrigerant in the tube will vaporize at this low pressure unless the tube is cooled. The liquid refrigerant enters the tube at the temperature of the condenser and, therefore, is quite warm. Considerable heat must consequently be removed from the refrigerant liquid in the capillary tube to reduce vaporization therein to reasonable values. One way of accomplishing this result is to place the capillary tube in heat exchange relationship with the suction tube which connects the evaporator and the compressor. The cooling effect of the suction tube on the capillary tube, however, is limited.

One object of this invention, therefore, is to cool the capillary tube by means other than or in addition to the refrigerant in the suction tube.

Another object of the invention is to utilize the cooling means used in cooling the condenser for cooling the capillary tube.

These and other objects are effected by my invention as will be apparent from the following description and claims taken in connection with the accompanying drawing and forming a part of this application, in which:

Fig. 1 is a front elevation of the device for cooling both the condenser and the capillary tube;

Fig. 2 is an end elevation of the device of Fig. 1;

Fig. 3 is a schematic drawing of the refrigerating apparatus in which the cooling device of this invention is incorporated; and

Fig. 4 is similar to Fig. 2 but shows a modification of the invention.

Referring now to the drawing for a detailed description of the invention, reference numeral 10 represents an insulated cabinet and 11 an evaporative cooling unit therein. The cooling unit 11 is of a box-like construction to accommodate ice trays 12. The vaporized refrigerant is withdrawn from the evaporator 11 through a suction tube 13 by a compressor 14. Compressed refrigerant vapor is conducted from the compressor 14 to condenser tubing 15 by a duct 16. The condenser 55

tubing 15 is bent sinuously and is secured to one edge of a series of parallel and spaced apart metal plates 17 between which air is drawn by a fan 18 to cool the tubing 15. The condensed and liquefied refrigerant passes through a screening device 19 at the lower end of the tubing 15 and then passes through a capillary tube 22 which conducts the liquid refrigerant to the bottom of the evaporator 11.

A portion 23 of the capillary tube 22 is likewise bent sinuously and is secured to the edges of the metal plates 17 lying opposite the edges to which the tubing 15 is secured.

The fan 18 is driven by a motor 24 and the compressor 14 by the motor 26. The motor 26 receives its energy from lines 27 and a switch 28 is included in one of these lines 27 and is adapted to be closed by a sylphon bellows 29 which communicates through a tube 31 with a bulb 32 secured to the evaporator 11. The bulb 32 contains a volatile liquid which vaporizes when the temperature of the evaporator 11 exceeds a predetermined point. The pressure of this vapor expands the sylphon bellows 29 and closes the switch 28, thereby starting the refrigerating apparatus. When the refrigerant has reduced the temperature of the evaporator 11 to the required degree, the bellows 29 contracts, opens the switch 28, and stops the motor 26.

The portion 23 of the capillary tube 22 is preferably placed on the edges of the plates 17 at which the cooling air enters the cooling device so that the heat of the refrigerant liquid in the portion 23 is reduced substantially to the temperature of the air. A second portion 34 of the capillary tubing 22 may be placed in heat exchange relationship with the suction tube 13 preferably by soldering portion 34 of the capillary tubing 22 to the suction tube 13. This heat exchange further cools the refrigerant liquid in the capillary tube and also vaporizes any liquid refrigerant which may have entered the suction tube 13 before it reaches the compressor 14. By cooling the capillary tube portion 23 by means other than the cool portions of the refrigerating circuit a clear gain in efficiency results because the heat is removed from the system and does not travel through the evaporator and compressor. Furthermore, by supplying substantially all liquid to the evaporator 11, the efficiency of the system is increased because the compressor 14 pumps substantially only gas which has vaporized in the evaporator and performed useful cooling.

Fig. 4 shows a modification of the invention in which the portion 23 of the capillary tubing 22 is

cooled by cooling fins 17a. Separate cooling fins 17b are utilized in cooling the condenser tubing 15. The portion 23 of the capillary tubing may also utilize a separate cooling medium from that employed in cooling the condenser.

While I have shown my invention in but two forms, it will be obvious to those skilled in the art that it is not so limited, but is susceptible of various changes and modifications without departing from the spirit thereof, and I desire, therefore, that only such limitations shall be placed thereupon as are specifically set forth in the appended claims.

1. In refrigerating apparatus, the combination of an insulated cabinet, an evaporator for cooling the interior of said cabinet, a compressor for withdrawing vaporized refrigerant from said evaporator, a suction tube connecting the evaporator and the compressor, a condenser tubing for receiving compressed refrigerant vapor from the compressor, means for conducting refrigerant liquid from the condenser to the evaporator, said means including a capillary flow impeding tube, cooling fins secured to both said capillary tube and said condenser tubing, and means for conducting a cooling medium along said cooling fins to first contact the portion thereof adjacent the capillary tube and thereafter the portion thereof adjacent the condenser tubing, a portion of said capillary tube and a portion of said suction tube being in heat exchange relationship.

2. In refrigerating apparatus, the combination of an insulated cabinet, an evaporator for cooling the interior of said cabinet, a compressor for withdrawing vaporized refrigerant from the evaporator, a condenser for receiving the compressed refrigerant vapor from the compressor, means comprising a conduit having at least a portion of relatively small cross-section and great length for conducting liquid refrigerant from the condenser to the evaporator and impeding the flow of said liquid to maintain a pressure differential between the condenser and the evaporator to cause liquefaction of the refrigerant in the condenser, said conduit being directly connected to the condenser in such a manner that substantially no excess refrigerant liquid is trapped therebetween, means for conducting heat from the exterior surface of said portion of the conduit, and means for effecting a flow of a cooling fluid other than said refrigerant over said last-named heat conducting means.

3. In refrigerating apparatus, the combination of an insulated cabinet, an evaporator for cooling the interior of said cabinet, a compressor for withdrawing vaporized refrigerant from the evaporator, a condenser for receiving the compressed refrigerant vapor from the compressor, means comprising a conduit having a relatively small cross-section and great length for conducting liquid refrigerant from the condenser to the evaporator and impeding the flow of said liquid to maintain a pressure differential between the condenser and the evaporator to cause liquefaction of the refrigerant in the condenser, said conduit being directly connected to the condenser in such a manner that substantially no excess refrigerant liquid is trapped therebetween, means for conducting heat from the exterior surface of a portion of said conduit, means for effecting a flow of

a cooling fluid other than said refrigerant over said last-named heat conducting means, and means for effecting heat exchange between a second portion of said conduit and the relatively cool refrigerant vapor withdrawn from the evaporator, said second portion being subsequent to said first portion with respect to the refrigerant flowing through the conduit.

4. In refrigerating apparatus, the combination of an insulated cabinet, an evaporator for cooling the interior of said cabinet, a compressor for withdrawing vaporized refrigerant from the evaporator, a condenser comprising a container for receiving compressed refrigerant vapor from the compressor, means forming a passage at least in part of small section and great length for conducting the liquid refrigerant from the condenser to the evaporator and impeding the flow of said liquid to maintain a pressure differential between the condenser and the evaporator sufficient to cause liquefaction of the vaporized refrigerant in the condenser, said passage being directly connected to the condenser in such a manner that substantially no excess refrigerant liquid is trapped therebetween, means for conducting heat from the exterior surfaces of said passage-forming means and of said container, and means for causing a common cooling medium to flow over the last-named means to cool the same.

5. In refrigerating apparatus, the combination of an insulated cabinet, an evaporator for cooling the interior of said cabinet, a compressor for withdrawing vaporized refrigerant from said evaporator, a condenser for receiving compressed refrigerant vapor from said compressor, said condenser including heat-dissipating fins, means for causing a cooling medium to flow over said fins to cool and liquefy the refrigerant vapor in said condenser, and means for conducting the liquid refrigerant from the condenser to the evaporator, at least a portion of said last-mentioned means comprising a capillary tube, said capillary tube being directly connected to the condenser in such a manner that substantially no excess refrigerant liquid is trapped therebetween, said tube being in heat-exchange relationship with said fins to cool the liquid refrigerant in the capillary tube.

6. In refrigerating apparatus, the combination of an insulated cabinet, an evaporator for cooling the interior of said cabinet, a compressor for withdrawing vaporized refrigerant from said evaporator, a condenser for receiving compressed refrigerant from said compressor, said condenser including a conduit and heat-dissipating fins, means for causing a cooling medium to flow over said fins to cool and liquefy the refrigerant vapor in said condenser, and means for conducting the liquid refrigerant from the condenser to the evaporator, said means including a capillary tube in heat-exchange relationship with said fins to cool the liquid refrigerant in the capillary tube, said capillary tube being directly connected to the condenser in such a manner that substantially no excess refrigerant liquid is trapped therebetween, the position of said tube on said fins being in advance of the position of said conduit on said fins with respect to the direction of flow of the cooling medium.
